UNITED STATES PATENT OFFICE

THOMAS M. TUTTLE, OF MOUNDS, OKLAHOMA

PUMP-JACK CONSTRUCTION

Application filed November 26, 1928. Serial No. 321,936.

The present invention relates to improvements in pump jacks and has reference more particularly to a jack that is used in pumping oil wells.

5 One of the important objects of the present invention is to provide a pump jack that includes a steel frame, it being an additional object to provide a jack that is provided with adjustable bearings for the various parts 10 thereof.

A further object is to provide a pump jack of the above mentioned character wherein the adjustment for the bearings may be readily and easily made whenever necessary.

15 Still a further object is to provide a pump jack of the above mentioned character which is simple in construction, inexpensive, strong and durable, and further well adapted to the purpose for which it is designed.

20 Other objects and advantages of the invention will become apparent from the following description when taken in connection with the accompanying drawing.

In the accompanying drawings wherein 25 like reference characters indicate corresponding parts throughout the same:

Figure 1 is a side elevation of the pump jack embodying my invention.

Figure 2 is a top plan view thereof.

30 Figure 3 is an end elevation.

Figure 4 is a sectional view taken approximately on the line 4—4 of Figure 1 looking downwardly.

Figure 5 is a vertical section taken approximately on the line 5—5 of the same figure looking in the direction of the arrow.

Figure 6 is a similar section taken approximately on the line 6—6 of Figure 1, and

40 Figure 7 is a detail perspective view of the bearing block provided for the bell crank unit of the pump jack.

In the drawings wherein for the purpose of illustration is shown the preferred embodiment of my invention, the numerals 1 and 2

45 designate a pair of parallel spaced longitudinally extending base plates or strips that are interconnected together as at 3. These base members may be set either on concrete blocks or wooden sills.

50 A substantially inverted U-shaped steel

frame denoted generally by the numeral 4 as the free ends of the arms thereof disposed laterally to provide attaching feet 5 that are secured on the forward end portion of the base member 1. A similar inverted U-shaped steel frame 6 is similarly secured on the forward end portion of the other base member 2 and these U-shaped frames are arranged in alignment with each other as clearly indicated in the drawings.

Upon referring to Figure 1 it will be observed that a substantially inverted U-shaped bracket 7 is secured within the upper portion of each inverted U-shaped steel frame so that the crown portion of the U-shaped bracket will be spaced below the crown portion of the respective inverted U-shaped frame and arranged for slidable movement between the bracket 7 and the top portion of each U-shaped frame is a bar 8. The ends of these blocks are spaced with respect to the arms of the frames and adjusting screws 9 extend through the respective arms of each inverted U-shaped frame, the inner ends of these screws being in engagement with the respective blocks 8 and a nut 10 is threaded on each set screw for holding the same in its properly adjusted position. By manipulating the set screws 9 and the nuts 10, the bearing blocks may be properly adjusted within the upper portion of the respective steel frame. The inner opposed faces of the bearing blocks are formed with suitable sockets for receiving the pintles 11 that project from opposite sides of a plate-like unit 12 that has formed on the bottom thereof the block 13 as clearly indicated in Figure 5. The pinions 11 cooperate with the sockets 15 to permit the pivotal movement of the unit 12 between the upper portions of the frames 4 and 5.

A jack beam denoted generally by the numeral 15 includes a pair of parallel spaced side plates 16 with spacing blocks 17 arranged therebetween and the forward ends of the side plates 16 are fixedly secured to the opposite sides of the block 13 whereby the forward end of the jack beam 15 is operatively connected with the vertically swinging unit 12. A polish rod grip bearing 18 is arranged on the upper rear end of this jack beam.

Suitable braces 19 are provided for the steel frames 4 and 5, and these braces extend from the rear ends of the base strips to the upper rear side portions of the respective frames.

5 A pair of alined inverted U-shaped brackets 20 and 21 are secured on the upper faces of the intermediate portions of the base strips 1 and 2 respectively and arranged for longitudinal adjustment within each bracket is the block 22. Suitable adjusting screws 23 extend through the respective arms of each of the inverted U-shaped brackets for engagement with the respective ends of the blocks 22 and nut 24 cooperates with each screw to hold the same in its properly adjusted position.

10 The blocks that are operable within the respective brackets are interconnected with each other, the interconnecting portion 25 has its upper face cut out to accommodate the rounded trunnions 26 that project from the opposite sides of a plate like member 27 and on which plate like member is formed the upper standing blocks 28 as clearly indicated in Figure 7. This construction provides a means whereby the unit 29 is rockably supported on the upper face of the connecting portion 25 for swinging movement between the spaced 15 brackets 20 and 21 and attached to this unit is the horizontal portion of a substantially bell crank lever denoted generally by the numeral 30.

20 This bell crank lever consists of a horizontal and a vertical arm. The horizontal arm includes the spaced side plates 31 that are disposed on opposite sides of the block 28 of the unit 29 inwardly of the forward ends of the side plates and these side plates are secured in a rigid manner to the blocks 28 by the appropriate fastening means. An additional block 32 provides spacing means for the rear end of the side plates of the horizontal arm of the bell crank lever.

25 The vertical arm of the bell crank lever also includes a pair of spaced side plates denoted by the reference character 33, and suitable spacing blocks 34 are interposed between the side plates 33. The lower extremities of the side plates of the vertical arm are fixedly secured to the forward extremities of the side plates of the horizontal arm of the bell crank lever, while diagonally disposed braces 35 extend between the upper end of the vertical arm and the rear end of the horizontal arm of this bell crank lever.

30 A shackle rod bearing 36 is associated with the upper end of the vertical arm of the bell crank lever 30 as indicated in Figure 1.

35 A pitman 37 extends between the rear end of the jack beam 15 and the rear end of the horizontal arm of the bell crank 30, and the top bearing for the pitman is shown generally at 38 while the lower bearing for the pitman is indicated at 39 in Figure 1.

As the operation of the pump jack is well known in the art, it is thought a detailed description of the same is believed unnecessary.

The provision of a pump jack of the above mentioned character renders the frame strong and durable and furthermore the bearings for the various pivotal elements of the pump jack are capable of being adjusted whenever necessary, and said adjustment may be made without difficulty.

70 While I have shown the preferred embodiment of my invention it is to be understood that minor changes in the size, shape and arrangement of parts may be resorted to without departing from the spirit of the invention and the scope of the appended claim.

75 Having thus described the invention, what I claim as new and desire to secure by Letters Patent is:—

80 A pump jack comprising a supporting structure including a base and a pair of inverted U-shaped frames rising vertically from one end of the base and in alinement with each other, bearing blocks slidably mounted in the upper portion of the respective frames, means adjustably securing the bearing blocks in the frames, a rocker unit rockably supported by the said bearing blocks and having a block like extension depending between the bearing block, a jack beam including spaced side plates fixedly attached to opposite sides of the said block like extension of the rocker unit, a bell crank lever mounted in said supporting structure, and a pitman connection between the said lever and the jack beam.

85

90 95 In testimony whereof I affix my signature.

100 THOMAS M. TUTTLE.
